UNITED STATES PATENT OFFICE.

CARL E. BAUER, OF HAMMOND, INDIANA.

DRAW-BAR YOKE.

1,339,940.

Specification of Letters Patent. Patented May 11, 1920.

Original application filed October 21, 1918, Serial No. 259,065. Divided and this application filed May 21, 1919. Serial No. 298,744.

To all whom it may concern:

Be it known that I, CARL E. BAUER, a citizen of the United States, and resident of Hammond, in the county of Lake and State 5 of Indiana, have invented certain new and useful Improvements in Draw-Bar Yokes, of which the following is a specification.

My invention relates to draft rigging for railway cars and particularly to a novel yoke 10 for use in connection therewith.

This application is a division of my co-pending application Serial No. 259,065, filed October 21, 1918 now Patent No. 1,330,575 Feb. 10, 1920.

15 One of the principal objects of my invention is to provide a draft rigging yoke which may be economically constructed and which when completed will have the rigidity and strength of a cast yoke and be of much 20 lighter weight. It is well known that it is desirable to provide a sleeve or head adapted to surround the draw bar butt and to connect the yoke arms to the sleeve. The difficulty encountered has been in providing 25 means of attachment between the yoke arms and the sleeve. In my construction I provide a rigid connection of great strength, which connection may be made without unusual expense. The principal object in de- 30 signing this form of connection has been to avoid looseness without perforating and thereby weakening the ends of the yoke arms. The result is accomplished in my construction by inserting the ends of the yoke 35 arms within the sleeve, bending the ends back over the forward edges of the sleeve, shoulders being provided adapted to abut the rear edges of the sleeve. As the yoke arms are assembled and bent while hot, the 40 cooling thereof will cause such contraction as to rigidly secure the parts in proper relation. In addition I may prefer to spot-weld the sleeve and arms, thus insuring a rigid connection.

45 The invention will be more readily understood by reference to the accompanying drawing, wherein,

Figure 1 is a longitudinal sectional view through a yoke constructed in accordance 50 with my invention;

Fig. 2 is a sectional view on the line 2—2 of Fig. 1, and,

Fig. 3 is a perspective view of the sleeve which I employ.

In constructing the yoke as shown herein, 55 I provide a sleeve member 10, having apertured ears 11, through which a fastening key is adapted to be passed. The sleeve or head is adapted to surround a draw bar yoke and serve as a means of attachment for the arms 60 12, 13, of the yoke. The bar from which the yoke arms are formed is bent into U-shape and the intermediate portion thereof is upset or thickened, as at 14. The forward ends are provided with shoulders 15, adapted to 65 abut the rear edges of the sleeve 10, when the parts are assembled. In forming the yoke the free ends thereof are heated, then inserted into the sleeve and the projecting ends 16, shown in dotted lines in Fig. 1, are bent 70 backward over the rounded forward edges of the sleeve. When cool, there will be sufficient contraction to firmly bind the yoke onto the sleeve. In addition I may spot-weld the two thicknesses of metal, as indicated at 75 17.

A yoke formed in the manner described may be constructed very cheaply, in fact more cheaply than a cast yoke. The parts are joined without the use of rivets or any fastening device which necessitates perforating and thereby weakening the parts. 80

I claim:

1. In a draft rigging device, the combination of a band adapted to surround and engage a coupler butt, a yoke member comprising a back wall and parallel arms, the free ends of the arms being provided with shoulders on their outer surfaces, and the ends of the arms being bent back upon themselves around the forward edges of the band, 90 said shoulders being adapted to engage the rear edges of the band, the hooks formed by the backwardly bent ends of the arms being of such depth as to overlie a portion of the band, substantially as described. 95

2. In a draft rigging device, the combination of a band adapted to surround and engage a coupler butt, a yoke member comprising a back wall and parallel arms, the free ends of the arms being provided with 100

shoulders on their outer surfaces, and the ends of the arms being bent back upon themselves around the forward edges of the band, said shoulders being adapted to engage the rear edges of the band, the hooks formed by the backward bent ends of the arms being of such depth as to overlie a portion of the

band, the arms being joined to the band by welding, substantially as described.

Signed at Hammond, Ind., this 17th day 10 of May, 1919.

CARL E. BAUER.
